UNITED STATES PATENT OFFICE.

JESSE S. PEVEAR, OF SCHENECTADY, NEW YORK, ASSIGNOR TO GENERAL ELECTRIC COMPANY, A CORPORATION OF NEW YORK.

RELAY AND METHOD OF MAKING THE SAME.

No. 923,202.

Specification of Letters Patent.

Patented June 1, 1909.

Application filed August 24, 1907. Serial No. 390,046.

To all whom it may concern:

Be it known that I, JESSE S. PEVEAR, a citizen of the United States, residing at Schenectady, county of Schenectady, State 5 of New York, have invented certain new and useful Improvements in Relays and Methods of Making the Same, of which the following is a specification.

My invention relates to relays in which a 10 core of magnetic material is movably supported within a current-carrying coil. Said core usually carries one or more contact members which move into and out of engagement with fixed contacts as the core is 15 drawn into the magnetic field of the current-carrying coil, or is allowed to drop from said field.

It is well known that when a spiral conductor is carrying current there is a tendency 20 for the convolutions of the spiral to approach one another, or in other words, a tendency for the coil to contract. Experience has shown that when the current-carrying coils of relays are rigidly supported 25 at their ends, a sudden large rush of current, and the resulting tendency for the coil to contract, may so strain the coil and supporting brackets that the whole structure gets out of line. Under these conditions the 30 coil may take a permanent "set" and interference with the movement of the core result.

An object of my invention is to so construct and support the current carrying coil that such disarrangement of parts cannot 35 occur. For this purpose I use a new method of making the coil and provide means for permitting contraction and expansion thereof without subjecting the supporting parts to any strain.

40 In the type of relay which I have selected for the purpose of illustration, the coil is rigidly supported at its lower end, while the other end is left free to move, electrical connection being made at the lower end 45 through the supporting means, and at the upper end through a flexible conductor. I wish it understood, however, that it is not my intention to limit myself to this particular construction, since I realize that the 50 coil might equally well be supported from its upper end, from its middle, or in many other ways.

The drawing shows in front elevation, partly in section, a relay constructed in accordance with my invention.

The various parts of the relay are supported on a base 1 of some suitable insulating material. The current-carrying coil 2 is preferably made by cutting spirally through a tube of copper or other suitable 60 conducting material. After the tube is cut in this manner it is placed in a press and the convolutions of the spiral pressed together. When the pressure is relieved the turns spring apart and leave a slight space 65 between each turn. The coil is thus allowed to take its natural position, and any contraction of it thereafter cannot give it a permanent set. This coil 2 is supported by the bracket 3 secured to a terminal 4 mounted 70 on the base 1. The upper end of the coil has secured to it a plate 5 connected by a flexible conductor 6, preferably of thin ribbons of copper, with a terminal 7.

Projecting downwardly from a bracket 8, 75 secured to the base 1, is an iron core 9, surrounded by a tube of insulation 10 which has an apron 11 of insulating material extending laterally therefrom outwardly over the top of the coil 2. The insulating tube 10 80 may be secured to the core 9 by means of a pin 12 passing through both, or in any other suitable manner. A movable core 13 has, extending from its upper end, a rod 14 which projects into and slides within a hole in the 85 core 9, as clearly shown. Secured to the lower end of the core 13, in any suitable manner as by screwing in into a threaded hole in said core and locking it with a lock-nut 15, is a rod 16. Loosely mounted on this rod 90 16, between collars 17 and 18 fixed thereon, is a contact disk 19 of a well-known type. A spiral spring 20 tends to keep this disk in engagement with the upper collar 17. Projecting from the lower end of the rod 16 is a 95 pin 21 arranged to slide in a hole in the end of a member 22 which screws through a fixed bracket 23, being held from movement by a lock-nut 24. The disk contact 19 when raised bridges the fixed contacts 25 and 26 100 supported on the base 1 in any suitable and well-known manner.

With the construction above described, it is clear that any contraction of the coil 2, due to a sudden rush of current, will not subject any of the parts to strain, since the top of the coil will be free to move up and down slightly, electrical connection with the terminal 7 being maintained by the flexible conductor 6.

The normal operation of the above described relay is as usual in devices of this kind. When the current in the coil 2 reaches a certain value the resulting magnetic field 5 causes the core 13 to rise, thereby lifting the contact disk 19 which bridges the fixed contacts 25 and 26, being firmly held in contact with them by a spring 20 which is put under tension.

10 While I have shown my invention as applied to a relay, it is, of course, to be understood that current-carrying coils may be made by my new method and supported in a manner similar to that which I have described 15 in connection with other types of electrical apparatus, such as circuit breakers, electro-magnetic switches, etc. It is my intention to cover my invention for all such uses and for all obvious modifications in the 20 following claims.

What I claim as new and desire to secure by Letters Patent of the United States, is,—

1. The method of making current-carrying coils which consists in cutting a spiral 25 through a tube of conducting material, pressing together the turns of the coil thus formed, and thereafter allowing the coil to expand to its natural position.
2. The method of making a current-carrying coil which consists in cutting spirally through a tube of conducting material, then pressing longitudinally the coil so formed, and thereafter allowing the coil to assume its natural position.
3. In an electro-magnetically controlled device, a current-carrying coil, a core of magnetic material movable in the field thereof, and means for supporting said coil so as to permit contraction and expansion thereof.
4. In an electro-magnetically controlled device, a current-carrying coil, a core of

magnetic material movable in the field thereof, means for rigidly supporting said coil from one end while the other end is left free to move.

5. In an electro-magnetically controlled device, a current-carrying coil, a core of magnetic material movable in the field thereof, means for supporting said coil from one end thereof and for making electrical connection with said end, and yielding means for making electrical connection with the other end of said coil.

6. In an electro-magnetically controlled device, a current-carrying coil, a core movable in the field thereof, fixed contacts, a contact supported by said core and arranged to move into and out of engagement with said fixed contacts as the core moves, means for rigidly supporting said coil at one end and for making electrical connection with the coil at that point, and a flexible conductor attached to the other end of said coil for making electrical connection therewith.

7. In an electro-magnetically controlled device, a current-carrying coil, a core movable in the field thereof, fixed contacts, a movable contact carried by said core and adapted to move into and out of engagement with said fixed contacts as the core moves, a bracket for rigidly supporting said coil at its lower end and making electrical connection therewith, and a flexible conductor attached to the upper end of said coil and making electrical connection therewith.

In witness whereof, I have hereunto set my hand this 23rd day of August, 1907.

JESSE S. PEVEAR.
